NAPKIN DISPENSER

Paul H. Horwitt, Hartsdale, N. Y., assignor, by
mesne assignments, to The Marathon Paper
Mills Company, Rothschild, Wis., a corporation
of Wisconsin

Application October 17, 1934, Serial No. 748,577

2 Claims. (Cl. 312—62)

This invention relates to a dispenser and more particularly to a dispenser for folded paper articles, such as paper napkins and the like.

According to my present invention, a follower 5 mechanism is provided for advancing articles within the dispenser in such a manner as to maintain the articles in proper position to be dispensed and also to exert against the articles a constant pressure uniformly urging the folded 10 articles towards the dispensing opening. Means are provided for preventing the follower mechanism from becoming jammed or from binding in its action.

It is therefore an important object of this 15 invention to provide a dispenser for folded paper articles of an improved construction, whereby the dispensing of such articles is facilitated.

It is a further important object of this invention to provide a follower mechanism for dispensers that is simple in its operation and functions smoothly without binding.

It is a further object of this invention to provide a dispenser for folded paper napkins and the like wherein a follower member is supported from 25 the side walls of the dispenser out of contact with the bottom wall so as to maintain the follower plate at all times in a vertical plane.

Other and further important objects of this 30 invention will be apparent from the disclosures in the specification and the accompanying drawing.

This invention (in a preferred form) is illustrated in the drawing and hereinafter more fully described.

35 On the drawing:

Figure 1 is a side elevation of a dispenser for folded paper napkins and the like, embodying the principles of my invention.

Figure 2 is a sectional view taken substantially 40 on the line II—II of Fig. 1.

Figure 3 is a sectional view taken substantially on the line III—III of Fig. 2, showing the operation in dotted lines.

As shown on the drawing:

45 The reference numeral 10 indicates generally a dispenser embodying the principles of my invention. Said dispenser 10 comprises an elongated container or receptacle 11, preferably rectangular in cross section, made from sheet metal or the like. Said container 11 is formed with a rear wall 12 having lateral flanges 13 overlying and secured to side walls 14 and 15. Said side walls 14 and 15 may suitably be formed integrally with a bottom wall 16. A front wall 17, having 50 a dispensing opening 18 is provided with lateral 55

flanges 19 adapted to overlie and be secured to the side walls 14 and 15. Said side walls 14 and 15 are provided with longitudinally extending slots 20 and 21, slightly above the middle height thereof, for a purpose that will later appear. 5

The follower mechanism for the dispenser 10 comprises a follower plate 22 of generally rectangular shape and of slightly smaller dimensions than the inner cross sectional dimensions of the container 11. Said follower plate 22 is provided 10 at its rear face with a flanged cross member 23, the flange 24 of which is secured to the rear face of the follower plate 22, as by brazing, welding or the like. Said cross member 23 extends laterally beyond the edges of the follower plate 22 to 15 project through the slots 20 and 21 as at 25 and 26, respectively. Beyond the side walls 14 and 15, the extended portions of the cross member 23 are bent downwardly to provide guiding flanges 27 and 28, respectively, overlying the adjacent 20 portions of the side walls. Angle pieces 29 and 30 are secured to said cross member 23 to provide upstanding guiding flanges 31 and 32, respectively, which overlie and are adapted to bear against the inner surfaces of the side walls 14 and 15. 25 The cross member 23, in combination with the downturned flanges 27 and 28 and the upturned flanges 31 and 32, provide a carrier for the follower plate 22 cooperating with the guiding slots 20 and 21 to support the follower plate 22 above 30 the bottom wall 16 and maintain said follower plate in a vertical plane throughout its movement longitudinally of the container.

Movement of the follower plate 22 is effected by means of a pair of coiled springs 33 and 34, 35 which are secured at their forward ends to the flanges 27 and 28, respectively, as at 35 and 36. Said springs 33 and 34 are trained around pulleys 37 and 38, mounted on the side walls 14 and 15, respectively, and the rearward ends of said 40 springs are secured to said side walls 14 and 15, as at 40. Said springs 33 and 34 are thus held under tension so as to constantly urge the follower plate 22 toward the front or dispensing wall 17. 45

As shown in Fig. 3, a stack of napkins 41 is adapted to be positioned between the follower plate 22 and the front wall 17 for dispensing through the opening 18. No particular form of napkin is required other than that it should be so 50 folded as to fit within the container 11 and present a free edge, such as the edge 42 for grasping and removal through the dispensing opening 18. In order to facilitate the removal of the napkins through the dispensing opening 18 without bind- 55

ing or becoming torn by contact with sharp edges, the edges of the dispensing opening 18 are bowed outwardly as at 43. Since the follower plate 22 is kept in constant vertical alignment by reason of 5 the cooperation between the guiding flanges 27, 28, 31, and 32 and the guiding edges provided by the slots 20 and 21, the napkins 41 are likewise maintained in vertical alignment and are not permitted to slump regardless of whether the 10 stack of napkins within the dispenser be large or small.

As shown in dotted lines in Fig. 3, the follower plate 22 is moved back into its rearward position at the time of filling the dispenser with a stack of 15 napkins. The tension of the springs 33 and 34 exerts a pull upon the follower plate 22 urging it forwardly toward the dispensing opening, thereby maintaining the napkins in proper position for dispensing.

20 The dispensing opening 18 is preferably considerably smaller in area than the napkins 41 to be dispensed therethrough, in order to provide substantial margins, such as the margins 44 and 45 (Fig. 3) for contact with the marginal portions 25 of the forwardmost napkins. In this way, only a single napkin can be removed at a time by grasping the edge 42 of the foremost napkin fold. This results in economy in the use of the napkins.

I am aware that many changes may be made 30 and numerous details of construction may be varied through a wide range without departing from the principles of this invention, and I, therefore, do not purpose limiting the patent granted hereon otherwise than necessitated by the prior 35 art.

I claim as my invention:

1. A dispenser for folded paper napkins comprising an elongated and rectangular container having a front wall provided with a dispensing 40 opening and being adapted to dispense napkins

having an edge thereof seated on the bottom of said container, each side wall of said container having a longitudinally extending slot in it, a carrier supported by said side walls, said carrier comprising a flat bar extending through said slots and resting on said side walls, said bar being provided with a pair of upwardly directed inner guiding members within said container and adjacent the inner face of the side walls thereof, and also being provided with a pair of downwardly directed outer guiding members adjacent the outer face of said side walls, spring means connected to said outer guiding members to urge said carrier towards said front wall, and a vertically extending follower plate secured to said carrier and supported thereby in spaced relation to the walls of said container. 5 10 15

2. A dispenser for folded paper napkins comprising an elongated and rectangular container 20 having a front wall provided with a dispensing opening and being adapted to dispense napkins having an edge thereof seated on the bottom of said container, each side wall of said container having a longitudinally extending slot in it, a carrier supported by said side walls, said carrier comprising a flat bar extending through said slots and resting on said side walls, said bar being provided with a pair of vertically directed inner guiding members adapted to have extended bearing 25 within said container and adjacent the inner face of the side walls thereof, and also being provided with a pair of vertically directed outer guiding members adjacent the outer face of said side walls, spring means connected to said outer guiding members to urge said carrier towards said front wall, and a vertically extending follower plate secured to said carrier and supported thereby in spaced relation to the walls of said container. 30 35
